UNITED STATES PATENT OFFICE.

JOHN ERNEWEIN, OF BUFFALO, NEW YORK.

DESIGN FOR A TABLE.

SPECIFICATION forming part of Design No. 16,723, dated June 8, 1886.

Application filed May 1, 1886. Serial No. 200,886. Term of patent 7 years.

To all whom it may concern:

Be it known that I, JOHN ERNEWEIN, of the city of Buffalo, in the county of Erie and State of New York, have invented and produced a new and original Design for Tables or Stands, of which the following is a specification.

This invention relates to a novel design for a table or stand; and it consists of the design which will be hereinafter described and claimed, and which is represented in the accompanying drawing, forming part of this specification.

A represents the top of the table, and B the legs thereof.

C represents diagonal braces arranged between the legs B near their lower ends.

D represents an ornamental hub or post arranged at the inner ends of the braces C.

E represents a shelf resting on the hub D.

F represents four round spindles extending 20 from the four corners of the shelf upwardly toward the under side of the top A of the table.

The essential feature of my design consists of the spindles F, extending from the corners 25 of the shelf upwardly toward the top of the table.

I claim as my invention—

The design for a table or stand herein shown and described, the same consisting of the top 30 A, legs B, diagonal braces C, hub D, shelf E, and spindles F, substantially as set forth.

Witness my hand this 24th day of April, 1886.

JOHN ERNEWEIN.

Witnesses:

OSCAR SCHAUB,
JNO. J. BONNER.
